DISPLAY ASSEMBLY

Milton S. Dunkelberger, Dayton, Ohio; Jack E. Dunkelberger, executor of the estate of said Dunkelberger, deceased, assignor to The American Display Company, Dayton, Ohio, a corporation of Ohio

Application November 15, 1954, Serial No. 468,901

10 Claims. (Cl. 40—106.41)

This invention relates to a display assembly. The invention relates more particularly to a display assembly in which a display object is movably attached to a display board or card. The invention relates still more particularly to a display assembly having a movable object attached thereto in which the movable object flutters and irregularly moves with respect to the board or card by which the movable object is supported. However, the invention is not so limited in that it relates to a device or assembly in which one member is movably attached to another member and in which means are provided to cause one member to flutter and to move irregularly with respect to the other member.

It is well known in the art of display assemblies that a display assembly provided with a movable object is much more attractive and gathers a person's attention much more readily than a display device which does not have a movable object thereon.

In the past a display assembly which was provided with movable objects has been rather expensive to construct and for that reason has been somewhat unpopular for simple types of display assemblies.

It is an object of this invention to provide a low cost display assembly having a movable object in which the movable object is caused to flutter and to move irregularly.

It is a further object of this invention to provide a display assembly in which one or more movable objects may be displayed along with one or more stationary objects.

It is a further object of this invention to provide a device having a stationary member and a movable member, the device including means for causing the movable member to move irregularly with respect to the stationary member.

Other objects and advantages reside in the construction of parts, the combination thereof and the mode of operation, as will become more apparent from the following description.

In the drawing,

Figure 1 is a fragmentary perspective view showing a typical display assembly of this invention.

Figure 2 is a side sectional view showing the operating devices of a display assembly of this invention.

Figure 3 is a side elevational view disclosing the operating devices of this invention showing the manner in which the movable members move with respect to the stationary members.

Figure 4 shows another typical display assembly made according to this invention.

Figure 5 is a side elevational view of a display assembly of this invention showing a preferred modification of the means for attaching a movable display object to the card or board member of the assembly.

Figure 6 is a side elevational view of a display assembly of this invention showing another modification of the attachment means for securing a movable display object

2

to a card or board member of the display assembly of this invention.

Referring to the drawing in detail, a typical display assembly of this invention comprises a display card or board 10, shown in Figure 1, supported substantially vertically by a wing-type of easel member 12. Attached to the display card 10 by means of a string or cord 14 is a display object 16, herein shown in the form of a girl in a running position carrying a plurality of books 17. It is observed that the display object 16 is a substantially flat member and is preferably made of rigid paper or cardboard material or any other suitable non-magnetic material.

Attached to the back side of the display object 16 is a permanent magnet 18, having a north and a south pole. The permanent magnet 18 is preferably of the bar type. However, any other suitable shape or type is satisfactory. The north and the south poles of the permanent magnet 18 may be disposed vertically with the north or south pole in the uppermost position, or the permanent magnet 18, may be disposed with the north and the south poles substantially horizontal, or in any other position. Attached to the permanent magnet 18 is a sponge rubber cushion 20 which is normally disposed against the front side of the card or board member 10.

At the rear side of the card or board member 10 is a bracket member 24 which is supported within a pocket 26. The bracket member 24 is composed of a non-magnetic material, such as, aluminum, or brass, or the like. Rigidly attached to the bracket member 24 is an electromagnet 27 which is attached to the bracket 24 by means of a magnetizable core member 28. The core member 28 is disposed at the back of the card 10 and is positioned at the portion of the card 10 which is adjacent the permanent magnet 18 at the front side of the card 10.

Surrounding the magnetizable core member 28 is an electric coil 30, to which are attached power supply wires 32, disposed within a flexible covering or conduit 34. It is to be understood that the electromagnet 27 may be supported adjacent the rear side of the card, or display member 10 by any suitable means other than the bracket member 24 positioned in the pocket 26. However, it has been found that in ease of assembly there are certain advantages in providing a pocket member which is adapted to removably retain a bracket, such as, the bracket 24.

The display assembly is disposed substantially vertically, as shown in the figures of the drawing. When it is desired to place the display assembly into operation, the coil 30 is energized by an alternating current. The electromagnet 27 is preferably adapted for use with an alternating current source of energy. However, a pulsating current or intermittent current supply may operate satisfactorily. Such energization of the coil 30 results in an alternating or intermittent magnetic flux which encompasses the permanent magnet 18 and affects the permanent magnet 18 so that the permanent magnet 18 is caused to flutter and jump irregularly. The suspension of the display object is such that the natural frequency of movement of the display object is not similar to the frequency of the flux created by the electromagnet. Thus, we have an object freely suspended which object is capable of a certain natural frequency of movement and the object is pushed or pulled at a rate different from the natural rate of the object. Thus, the movable display object 16, to which is attached the permanent magnet 18, is caused to flutter irregularly in its position adjacent the display card 10. Thus, the display object 16 is very active during energization of the coil 30 with an alternating, pulsating or intermittent current.

As shown in Figures 1 and 3, the display object 16 has irregular movements both parallel to the card 10

and normal to the card 10 during energization of the coil 30. This movement results in causing the display object 16 to be very attractive and of interest to anyone who may observe the display assembly. In order to obtain the greatest amount of activity of the movable display object 16, the permanent magnet 18 may be positioned so that the permanent magnet 18 is slightly out of line with the longitudinal axis of the core 28. However, it has been found that the permanent magnet 18 jumps and flutters satisfactorily when disposed in any position adjacent the core 28 of the electromagnet 27.

The sponge rubber member 20 which is attached to the permanent magnet 18 acts as a cushion between the magnet 18 and the card member 10 so that no appreciable noise results from the operation of the display object 16 as the display object 16 flutters and irregularly engages the card member 10. However, if the noise of the jumping and fluttering of a display object is desired, as well as the appearance thereof, the cushion 20 may be omitted.

In Figure 4 is shown a movable display object 35 in the form of a flying insect. To the movable display object 35 at the rearward side thereof is provided a permanent magnet (not shown), such as the permanent magnet 18. The back side of a card or board member 38, to which the movable display object 35 is attached, is provided with an electromagnet (not shown), similar to the electromagnet 27 shown in Figures 1, 2 and 3.

In the display assembly, shown in Figure 4, a stationary object 40 is attached to the card or board member 38. Therefore, the display assembly, as shown in Figure 4, is provided with both a stationary and a movable object. The card member 38 is also provided with any suitable type of lettering or indicia, as shown thereon at the upper portion thereof.

In Figure 5 is shown a side view of a modification of a display assembly of this invention in which a card or board member 42 is provided with a hook member 44. The hook member 44 loosely supports a movable display object 46 which is provided with a permanent magnet 48 having a cushion member 50 attached thereto. Adjacent the card member 42 at the rearward side thereof is shown a magnetic core 52, similar to the magnetic core 28 of the preferred embodiment. The magnetic core 52 is supported by means of a bracket member 53. It is noted that the permanent magnet 48 is disposed slightly below the level of the core 52. As stated above, any display assembly made according to this invention may have the permanent magnet thereof disposed in any relative position adjacent the end of a magnetizable core member, as evidenced by the figures herein. On the card 42 is also rigidly supported a stationary display object 54.

In Figure 6 is shown another modification in the means of attachment of a movable display object 56 to a card or board member 58. The movable display object 56 is attached to the card 58 by means of a spring member 60. Attached to the movable display object 56 is a permanent magnet 62 which is provided with a cushion member 64. Also shown at the rearward side of the card member 58 is a magnetizable core member 66, supported by a bracket 67.

A plurality of permanent magnet and electromagnet assemblies made according to this invention may be assembled upon a large display board to provide fluttering movement to a plurality of letters. Thus, the letters comprising a word or a sentence upon a display board may be caused to flutter irregularly.

It is to be understood that the structure of this invention may be employed in other types of devices and apparatus. The movable elements of this invention may be employed in any device in which it is desired to have a movable member which jumps and flutters with respect to another member of the device.

Although the preferred embodiment of the device

has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A flutter display assembly comprising a card member, a substantially flat display object movably supported by the card member on one side thereof, a permanent magnet attached to the display object and disposed intermediate the display object and the card member, an electromagnet disposed adjacent the card member on the other side of the card member and adjacent the permanent magnet attached to the display object, the permanent magnet being within the field of said electromagnet, and means for supplying alternating current energy to the electromagnet, the display object thus being caused to flutter when the electromagnet is supplied with alternating current energy.
2. A flutter display assembly comprising a support structure, a display object loosely supported by the support structure, an electromagnet supported by the support structure adjacent the display object, and a permanent magnet within the field of said electromagnet and attached to the display object, the display object thus being caused to flutter when the electromagnet is energized.
3. In a flutter display assembly comprising a thin support structure having a front surface and a rear surface, a display object movably supported by the support structure adjacent the front surface thereof, a permanent magnet attached to the display object and disposed intermediate the display object and the support structure, and an electromagnet provided with an alternating current energy supply attached to the support structure at the rear surface thereof, the permanent magnet being within the field of the electromagnet, the alternating current energy supply to the electromagnet causing an alternating flux field which affects the permanent magnet by causing the permanent magnet to flutter and to jump irregularly in its flexible attachment to the support structure.
4. A flutter display assembly comprising a substantially vertical support board member, a hook member attached to said board member, a display object loosely attached to said hook member and supported thereby, a permanent magnet attached to said display object intermediate the display object and the board member, a cushion member attached to the permanent magnet intermediate the permanent magnet and the board member, an electromagnet supported adjacent the board member and the permanent magnet, the permanent magnet being within the field of the electromagnet, and means for energizing the electromagnet with an alternating current, the display object thus being caused to flutter and to jump irregularly when the permanent magnet is affected by the alternating flux established by the electromagnet.
5. A flutter display assembly comprising a support structure, an electromagnet carried by the support structure, a display object flexibly supported by the support structure adjacent the electromagnet, a permanent magnet attached to the display object within the field of the electromagnet, and means for energizing the electromagnet with an electric current which is non-constant in value, the display object thus being caused to flutter and to move irregularly when the electromagnet is energized.
6. In a display assembly comprising a card member, a display object, a flexible spring member loosely attaching the display object to one side of the card member, a permanent magnet attached to the display object and disposed intermediate the display object and the card member, an electromagnet disposed adjacent the card member on the other side of the card member and adjacent the permanent magnet attached to the display ob-

ject, the permanent magnet being within the field of the electromagnet, and means for supplying current which is non-constant in value to the electromagnet, the electromagnet thus establishing a flux which causes the permanent magnet to flutter and to jump irregularly with respect to the card member.

7. A flutter display assembly comprising a support member, a display member movably supported by the support member, an electromagnet supported by one of said members, and a permanent magnet within the field of the electromagnet and attached to the other of said members, the display member thus being caused to flutter and to jump irregularly.

8. A flutter display assembly comprising a support member, a display member movably attached to the support member, a permanent magnet attached to the display member intermediate the two members, and an electromagnet provided with means for energization from a source having a changing voltage, the electromagnet being supported by the support member adjacent the permanent magnet, the permanent magnet being within the field of the electromagnet.

9. In a magnetic assembly having a flutter movement comprising an electrically controlled magnet having means for energization by a source having a changing voltage and a permanent magnet, the permanent magnet being within the field of the electrically controlled magnet, said

magnets being disposed in juxtaposed relation, said magnets being movably disposed one with respect to the other, the magnets thus moving one with respect to the other in a fluttering and irregular manner when the electrically controlled magnet is energized.

10. In a display assembly, the combination including support structure, an electrically operated magnet having means for energization by a source having a changing voltage and carried by the support structure, a display member movably carried by the support structure, and a permanent magnet attached to the display member and within the field of the electrically operated magnet, the display member thus fluttering and moving irregularly when the electrically operated magnet is energized.
